UNITED STATES PATENT OFFICE.

ERNEST A. GIESSER, OF BOSTON, MASSACHUSETTS.

VENTILATING-WINDOW.

SPECIFICATION forming part of Letters Patent No. 691,260, dated January 14, 1902.

Application filed May 16, 1901. Serial No. 60,441. (No model.)

To all whom it may concern:

Be it known that I, ERNEST A. GIESSER, of Boston, in the county of Suffolk and State of Massachusetts, have invented certain new 5 and useful Improvements in Ventilating-Windows, of which the following is a specification.

This invention has for its object to enable air to be admitted through the meeting-rails 10 of two window-sashes by slightly moving one of the sashes from its closed position, the admission of air being prevented when both sashes are fully closed.

The invention consists in the improvements 15 which I will now proceed to describe and claim.

Of the accompanying drawings, Figure 1 represents a perspective view showing portions 20 of two window-sashes embodying the invention and a portion of the casing in which they are contained. Fig. 2 represents a vertical section showing the two sashes closed. Fig. 3 represents a view similar to Fig. 2, showing the lower sash partly raised.

25 The same letters of reference indicate like parts or features in all the drawings wherever they occur.

On the drawings, *a* represents the meeting-rail of the inner sash of a window, and *b* represents the meeting-rail of the outer sash.

30 *c c* represent air-ducts extending transversely through the meeting-rail *b* from its outer to its inner side.

d d represent air-ducts extending through 35 the meeting-rail *a*, the ducts *d* extending from the outer side of said rail to its upper side or edge, so that air flowing through said ducts will be delivered in a direction parallel with the plane of the inner sash and will 40 not therefore move directly inward from the inner sash.

In the embodiment of my invention here shown the ducts *d* are angularly formed. The relative positions of the ducts *c* and *d* are 45 such that when both sashes are closed, as shown in Figs. 1 and 2, the ducts will be disconnected, so that no air can pass through them, and when the inner sash is slightly displaced from its closed position, as shown in 50 Fig. 3, the ducts are connected, so that air

will pass through them, as indicated by arrows.

The bead or strip *f* of the window-casing, which abuts against the lower rail *a'* of the inner sash, is of such height that it overlaps 55 the rail *a'* when the ducts *c* and *d* are connected, as shown in Fig. 3, so that it constitutes an air-guard which prevents the admission of air between the rail *a'* and the end of the casing, against which it abuts when closed. 60 It will be seen that the described improvement provides means whereby air may be admitted for the purpose of ventilation by slightly moving one of the sashes from its closed position, the admission of air being 65 confined to the region of the meeting-rails *a* and *b* and prevented when the sashes are closed. The described improvement may be applied to any window the meeting-rails of which have sufficient width to enable the 70 ducts *c* and *d* to be formed therein.

It is obvious that my invention may be applied to windows in which the sashes slide horizontally as well as to those in which the sashes slide vertically.

I claim—

1. A ventilating-window comprising an inner and an outer sash relatively movable in parallel planes and having air-ducts in their meeting-rails, the ducts of the inner sash being out of connection with the ducts of the outer sash when both sashes are closed, and adapted to be brought into connection with the ducts of the outer sash by a movement of the inner sash.

2. A ventilating-window comprising an inner and an outer sash relatively movable in parallel planes, the meeting-rail of the outer sash having transverse air-ducts extending from its outer to its inner side while the meeting-rail of the inner sash has air-ducts extending from its outer to its upper side, the ducts of the inner sash being out of connection with the ducts of the outer sash when both sashes are closed, and adapted to be 90 brought into connection with the ducts of the outer sash by a movement of the inner sash.

3. A ventilating-window comprising an inner and an outer sash relatively movable in parallel planes and having air-ducts in their 100

meeting-rails, the ducts of the inner sash being out of connection with the ducts of the outer sash when both sashes are closed, and adapted to be brought into connection with the ducts of the outer sash by a movement of the inner sash, and a casing having a guard member which overlaps the end rail of the inner sash sufficiently to prevent the entrance

of air when the inner sash is in position to connect the two series of ducts.

In testimony whereof I have affixed my signature in presence of two witnesses.

ERNEST A. GIESSER.
